WALL FINISHING MASONRY IMPLEMENT

Leo Haber, Riverdale, Md.

Application July 1, 1957, Serial No. 669,157

5 Claims. (Cl. 25—131)

This invention relates to masonry and more particularly to a finishing frame comprising a finishing implement for the soft top portion of a concrete wall and form thereof.

It is well known that the form of a concrete wall may spread unevenly especially at its top when the concrete is poured into the form.

This invention or implement when applied to the top portion of the concrete wall and form serves to straighten the top portion of the form and the wall and limit it to a substantially uniform desired thickness, and at the same time provide for the application of finishing material for the desired smooth straight finish.

This invention or implement is economical in use and is technically satisfactory in the finishing of concrete walls.

Other objects and advantages will be revealed in connection with the detailed description of the accompanying drawings, which constitute a part of this application.

In the drawings:

Fig. 1 is a fragmentary plan view of the implement.

Fig. 2 is a transverse section of the implement taken on the line 2—2 of Fig. 1.

Fig. 3 is a fragmentary sectional view showing how each bolt is applied to the implement.

Fig. 4 is a sectional view taken on the line 4—4 of Fig. 3.

Fig. 5 is a sectional view showing an adjustable means.

Fig. 6 is a sectional view showing the adjustable means, like that of Fig. 5, taken on the line 6—6 of Fig. 5.

Fig. 7 is a sectional view taken on the line 7—7 of Fig. 6.

Fig. 8 is a vertical section taken substantially on line 2—2 of Fig. 1, with the concrete applied.

This implement comprises a frame having two angle irons or steel bars 1 and 2 connected together fixedly by tubes 3 which are welded at their ends to the upright webs of the angle irons or steel bars.

The nuts 4 are welded to the upright webs of the steel bars 1 and 2 inside of the connecting tube ends.

Longitudinal channel bars 5 and 6 are provided to engage the uprights 7 of the concrete form. The screw threaded bolts 8 must be long enough to span the uprights 7 and also to pass through the channel bars and the webs as well as engage the nuts 4. The bolts may be seven or eight inches long more or less.

The implement may be eight feet long more or less and frame units are made respectively for an eight inch wall, ten inch wall, twelve inch wall etc. These constructions represent the preferred form or species.

In the modification shown in Figs. 5, 6 and 7 the connecting tubes 9 and 10 for the angle bars are telescopic, so that the angle bars may be adjustably spaced from each other to accommodate a wall thickness of eight inches, ten inches, twelve inches etc.

This modified unit can take the place of, at least three units of the preferred form or species.

2

In the modified form Figs. 5, 6 and 7 the telescopic tubes 9 and 10 must be provided with a series of suitably spaced transverse apertures 11 and 12 to receive removably transverse locking pins 13 and 14.

5 When a concrete wall reaches the finishing phase and its top portion 9' is still soft this implement is applied to the top of the concrete wall, so that the angle bars 1 and 2 rest on the top of the wall. The channel bars 5 and 6 engage the uprights 7 on the outside thereof 10 and when the implement is in proper position the bolts 8 are tightened sufficiently to straighten the wall and make it conform to the straightness of the implement frame and at the same time guage and force the wall to the desired thickness.

15 Finishing concrete material can now be applied between the bars 1 and 2 and finished off with a trowel substantially on a common plane coplanar with the plane defined by the lower surface portions of the horizontal webs of the angle bars 1 and 2.

20 When the concrete is sufficiently set or solidified then the implement can be removed and thereby leaving a substantially perfect finish to the top portion of the wall.

25 Fig. 8 is similar to Fig. 2 but is a more detailed disclosure, besides the concrete is shown. The sheeting of the form is indicated at 7' and the concrete is indicated by 8'.

30 Detailed modifications may be resorted to as long as they come within the purview of the metes and bounds of the claims presented. For example, the tubes may have screw threaded caps thereon (not shown). Each cap could be provided with a screw threaded aperture to receive the bolts. Each cap could be welded to the upright web of the angle bars or channel bars if substituted for the angle bars. Of course, channel bars could be substituted for the angle bars 1 and 2.

35 This implement is a finishing device for a soft concrete wall and is not a complete wall form. This implement is applied to the top of a soft concrete wall while the wall is still pliable. The members 5 and 6 engage the uprights 7 on both sides of the wall retained by the usual form. The lower webs of angle bars 1 and 2 engage the top of the wall as evenly as possible. Of course, the horizontal webs of bars 1 and 2 engage the top of the wall as much as possible and the lower surface portion of the webs of bars 1 and 2 define the top surface portion of the wall and may be finished by applying as much additional cement or concrete as may be necessary to finish the top portion of the soft concrete wall.

40 Of course, if the wall is not straight the bolts 8 can be tightened accordingly to straighten the wall and its form, especially the uppermost portion thereof while the wall is still soft and pliable.

45 Ordinarily, the finishing cement or concrete should be applied between the bars 1 and 2 after the wall has been straightened by the manipulation of the implement.

50 After a portion of the soft wall has been straightened the implement can be shifted longitudinally a suitable distance to straighten and treat an additional portion of the wall, and thus repeat the operation until the wall is completely straightened and finished.

55 Having fully described my invention and the operation thereof, what I claim is:

1. In a masonry implement comprising a long substantially rectangular frame having suitably spaced inner bars connected by a plurality of substantially uniformly spaced means, in combination with screw threaded nuts and screw threaded bolts in further combination with a pair of outer bars, each outer bar being located on the outside of the inner bars, said nuts being located on the inside of said inner bars and secured thereto, said inner bars having apertures therein in alignment with

said threaded nuts, said outer bars also having apertures therein in alignment with the apertured portions of said inner bars, said inner bars being adapted to lie on the top of the soft wall between the uprights of the usual form, said apertured portions of said outer bars carrying said adjustable screw threaded bolts in alignment, respectively, with said nuts and the apertured portions of the inner bars and adjustably connected thereto, whereby, said frame may be placed on top of a soft concrete wall with said inner bars on the inside of the uprights of the usual form and said outer bars on the outside of the uprights, said bolts may be adjusted in order to straighten the soft top portion of the wall and simultaneously guage the thickness of the soft wall.

2. In a masonry implement, said implement comprising a means for finishing the soft top portion of a concrete wall, said implement comprising a long rectangular frame in combination with spacer tubes, screw threaded bolts and complemental nuts, said frame further comprising a pair of parallel inner bars adapted to be placed on top of a soft wall between the uprights of the usual form, in combination with an outer pair of clamping bars, said inner bars being connected by said tubes, said tubes being uniformly spaced from each other between said inner bars, said nuts being secured to said inner bars and on the inside of said tubes at the ends thereof, said clamping bars being adapted to engage the uprights of the usual wall form on the outside thereof, said bolts connecting said clamping bars to said inner bars whereby the uprights of the form may be drawn together to straighten the top soft portion of the wall and guage the thickness thereof.

3. In a masonry implement, said implement comprising spacer tubes, screw threaded bolts and complemental nuts, and a long substantially rectangular frame, said frame having suitably spaced parallel inner bars, said bars being connected together in fixed relation by a plurality of said tubes uniformly spaced, said tubes having screw, and said threaded nuts at their ends in connection with the inner bars said inner bars being placeable between the uprights of the usual form, in combination with additional bars located in spaced relation from each other and located, respectively, on the outside of the inner bars in spaced parallel relation and also on the outside of the uprights of the usual form, each of said bars having, at least, one upright web and one horizontal web, said bars having apertures in their upright webs in alignment, respectively, with said screw threaded nuts, said bolts passing through the apertured portions of said bars and engaging, respectively, the threaded nuts, whereby when the frame is initially placed on top of the soft wall, the additional bars may engage the uprights on the outside thereof of the usual form and draw them together to straighten the top soft portion of the wall and simultaneously guage the thickness thereof.

4. In a masonry implement, said implement comprising spacer tubes, screw thread bolts and their complemental nuts and a long finishing frame for a soft concrete wall, said frame comprising a pair of inner bars arranged in substantially parallel spaced relation, said

bars being connected by a plurality of said spacer tubes, said tubes being uniformly spaced from each other, said nuts being welded to said bars, respectively, inside of the ends of said tubes, said inner bars being placeable on the top of a soft concrete wall between the uprights of the usual form, in combination with two additional bars arranged in substantially parallel relation to themselves and to the first mentioned bars and each bar located outside, respectively, of said first mentioned bars, said additional bars being locatable on the outside of the uprights of a usual concrete form, all of said bars having apertures therein arranged, respectively, in alignment with said nuts and screw threaded bolts, said bolts extending through the apertured portions of said bars and engaging said nuts, whereby said additional bars may be drawn uniformly together and toward said first mentioned bars to straighten the top portion of the soft wall and simultaneously guage the thickness of the top portion of the wall.

5. In a masonry implement, said implement comprising telescopic spacer tubes, screw threaded bolts and their complemental nuts, and a long finishing frame for a soft concrete wall, said frame comprising a pair of inner bars, said bars being substantially parallel and suitably spaced from each other, said bars being connected by said telescopic tubes, said tubes being arranged in substantially uniformly spaced relation relative to each other the outermost ends of said tubes being welded at said ends, respectively, to said bars said nuts being welded to said bars, respectively, inside the outer ends of said tubes, said inner bars being placeable on the top portion of a soft wall between the uprights of the usual form, in combination with two additional bars, said additional bars being arranged in spaced substantially parallel relation to themselves and to the first mentioned bars and each additional bar being located outside of said first mentioned bars, all of said bars having apertures therein arranged, respectively, in alignment with said nuts, said bolts extending through the aperture portions of said bars and engaging said nuts, whereby said additional bars may be drawn uniformly toward said first mentioned bars to straighten the top portion of the soft wall and simultaneously guage the thickness of the top portion of the wall.
